UNITED STATES PATENT OFFICE.

ROYAL E. BALL, OF NEW YORK, N. Y.

SPEED-REDUCING FRICTION-GEARING.

SPECIFICATION forming part of Letters Patent No. 651,410, dated June 12, 1900.

Application filed January 30, 1899. Serial No. 703,766. (No model.)

To all whom it may concern:

Be it known that I, ROYAL E. BALL, a citizen of the United States, residing at New York city, borough of Manhattan, county and State 5 of New York, have invented certain new and useful Improvements in Speed - Reducing Friction-Gearing, of which the following is such a full, clear, and exact description as will enable any one skilled in the art to which it 10 appertains to make and use the same, reference being had to the accompanying drawings, forming part of this specification.

My invention relates to means for reducing the speed of mechanism actuated by a drive- 15 shaft—for example, where a high-speed motor-shaft is used for driving machines or a vehicle.

The chief object of my invention is to provide a simple and efficient friction device for 20 gearing down or reducing the speed; and to such end my invention consists in the various novel and peculiar arrangements and combinations of the several parts of the device, all as hereinafter fully described and then pointed 25 out in the claims.

I have illustrated a type of my invention in the accompanying drawings, wherein—

Figure 1 is a sectional view of a device embodying my invention, the section being taken 30 on a vertical plane extending longitudinally through the center of the drive-shaft. Fig. 2 is a sectional view of the device, the plane of which is indicated by line 2 2, Fig. 1.

Referring to the drawings, in which like 35 numbers of reference indicate like parts throughout, 2 is the motor or drive shaft from which motion is to be transmitted to the desired mechanism at a reduced speed. This shaft, which may be, for instance, that of an 40 ordinary electric motor, is surrounded by a concentric rotary roller-cage, which in the present instance comprises a disk or member 3, arranged concentrically with the drive-shaft 2, at the outer end thereof, and provided 45 with a set of inwardly-projecting studs 4, which are fixed therein. These studs are set on a concentric circle and each carries a freely- 50 turning tubular roller 5, which revolves between the disk 3 and the head or flange 6 upon the end of the stud. These rollers are set

close to each other, but do not bind against each other, and the axes about which they revolve are each contained in the same plane with the axis of the drive-shaft 2, which they surround. The rollers 5 are so located that 55 the conical group which they form fit snugly around the drive-shaft 2, so that the rotary motion of the drive - shaft slowly revolves each of the rollers by frictional contact with the periphery of the rollers, and their revolutions in rolling around the drive-shaft and the outer stationary case 10 cause the frame or cage in which they are mounted to turn slowly in the same direction as the shaft. The disk 3 of the roller-cage has connected 65 with it a toothed gear 7, which consists in a toothed ring secured in fixed position upon the periphery of the disk 3, and the teeth of this gear mesh with a pinion 8, mounted on a shaft 9, so that the motion of the drive- 70 shaft 2 may be transmitted to the shaft 9 at a much-reduced speed through the intermediary of the roller-cage. The roller-cage is provided with a bushing 10, fixed in the journal-box 11. These parts are so arranged that 75 the peripheries of the rollers 5 are maintained in frictional contact with both the drive-shaft 2 and the interior of the bushing 10 when the drive-shaft is running.

While the invention contemplates the use 80 of cylindrical tubular rollers of uniform diameter throughout, operating in conjunction with a cylindrical portion of the drive-shaft, I propose, however, to form the tubular rollers like a truncated cone, so that the exterior 85 thereof tapers gradually from one end to the other, and to give to the portion of the drive-shaft adjacent the rollers a corresponding taper, so that the frustum-shaped rollers and part of the shaft have the same apex length. 90 Thus in the structure shown the outer end of the drive-shaft 2 is tapered, beginning at point 13, to its outer end, the smaller end of the taper being at the outer end. The rollers 5, which are of the same diameter as the tapered 95 portion of the shaft at each point where they make contact, are tapered and are disposed with their larger ends lying inwardly, as shown in the drawings. The bushing 10 is formed with an interior taper, with the smaller 100

end of the taper lying outwardly. In order to set the tapered rollers at the proper angle, I incline the rods or studs 4 slightly with reference to the axis of the roller-cage, and thereby cause the parts to run true.

In conjunction with the tapered rollers 5 of the roller-cage I arrange the drive-shaft 2 so that it has capacity of endwise movement and provide it with bearing 14, in which it may 10 turn whenever the shaft is drawn out from the roller-cage.

15 15 is a lever pivoted at 16 and provided with a circular bracket 17, encircling the drive-shaft and carrying inwardly-projecting pins 18 at opposite points thereon, which take loosely into the annular groove 19, formed around the exterior of the collar 20, fixed upon the shaft. By means of this lever the shaft may be shifted endwise, and normally the lever 20 is drawn outwardly by a spring 21, so that it keeps the conical end of the shaft jammed in the conical nest or set of rollers, so as to make good frictional contact between such conical portion of the shaft and each of the 25 rollers. The center of the outer end of the drive-shaft 2 bears upon a slightly-raised center or boss 22, formed upon the inner face of the disk 3 when the shaft is forced into the roller-cage, and this materially assists in steadyng 30 the parts when in motion and at the same time limits the distance that the drive-shaft can be forced into the roller-cage.

By having the tubular rollers of the same exterior diameters as the portion of the shaft 35 around which they roll each complete revolution of a roller serves to carry such roller once around the shaft.

In regard to the ratio of the speed of the drive-shaft to the speed of the concentric or 40 driven roller-cage I find that one is to the other as the external diameter of the roller-cage shaft is to the diameter of the drive-shaft. Expressed as a formula it is as follows: Speed of the drive-shaft divided by the 45 speed of the roller-cage equals the external diameter of the roller-cage divided by the diameter of the drive-shaft. For example, referring to Fig. 2, where $a\ b$ is the external diameter of the roller-cage and $c\ d$ is the diameter of the drive-shaft, the quotient of the latter into the former will give the speed ratio 50 between the drive-shaft and the roller-cage.

By virtue of this construction I am enabled 55 to provide a very simple and efficient speed-reducing gear which is well adapted for use with electric motors in reducing the speed thereof.

Having thus described my invention, what 60 I claim, and desire to secure by Letters Patent, is—

1. A speed-reducing friction-gear comprising the combination of an endwise-movable drive-shaft and means for moving the shaft 65 endwise, said shaft having a portion thereof

tapered and being provided with a bearing in which it rests when the shaft is moved away from the roller-cage, a rotary annular roller-cage provided with a set of rollers tapering in the reverse direction to the taper of the shaft, a journal-box concentric with said drive-shaft, said roller-cage being interposed between said journal-box and drive-shaft with its rollers in contact therewith and adapted to engage with the tapered surface 70 of said shaft when the shaft is moved endwise into the roller-cage, said roller-cage being provided with a gear member independent of said rollers, whereby the motion of the drive-shaft may be transmitted to said gear member at a reduced speed, substantially as and for the purpose set forth.

2. A speed-reducing friction-gear comprising the combination of a drive-shaft, a rotary annular roller-cage consisting in a gear-wheel 85 and a set of rods projecting from one face of the said gear-wheel and arranged in a circle thereon, a tubular roller loosely mounted on each of said rods, a journal-box concentric with said drive-shaft, said cage being placed 90 over one end of said shaft with the rollers arranged in rolling contact between the journal-box and the shaft, whereby the motion of the drive-shaft may be transmitted to said gear member at a reduced speed, substantially as and for the purpose set forth.

3. A speed-reducing friction-gear comprising the combination of an endwise-movable drive-shaft and means for moving the shaft endwise, a rotary annular roller-cage provided with a set of loosely-mounted rollers each having its axis in a plane containing the axis of the drive-shaft, a journal-box concentric with said drive-shaft, said roller-cage being interposed between said journal-box and 100 drive-shaft with its rollers in contact with the surface of each and being provided with an end plate or disk against the inner face of which the end of the drive-shaft is adapted to bear when moved endwise into the roller-cage, substantially as and for the purpose 105 set forth.

4. A speed-reducing friction-gear comprising the combination of an endwise-movable drive-shaft and means for moving the shaft 115 endwise, said shaft having its outer end tapered with the smaller part of the taper lying outwardly, and being provided with a bearing in which it rests when the shaft is moved inwardly, a journal-box concentric with said drive-shaft and tapered in the same direction as the tapered portion of the shaft; a roller-cage provided with a set of loosely-mounted rollers each having its axis in a plane containing the axis of the drive-shaft, said rollers being tapered in the same direction as the tapered portion of the shaft and being interposed between the same and said journal-box so as to have a rolling contact with each 125 of said parts, said roller-cage being provided 130

with an end plate or disk against the inner
face of which the end of the drive-shaft is
adapted to bear when said shaft is moved
into the roller-cage, said disk being provided
5 with a gear member, substantially as and for
the purpose set forth.

In testimony whereof I have hereunto set

my hand, this 26th day of January, 1899, in
presence of the two subscribing witnesses.

ROYAL E. BALL.
